UNITED STATES PATENT OFFICE

138,560

DESIGN FOR A COMBINED PAPER WEIGHT AND PHOTOGRAPH MOUNT

James A. Morehead, Huntington, W. Va., assignor to Sinclair Glass Company, Ceredo, W. Va., a corporation of West Virginia

Application November 18, 1943, Serial No. 111,719

Term of patent 7 years

(Cl. D74—12)

To all whom it may concern:

Be it known that I, James A. Morehead, a citizen of the United States, residing at Huntington, in the county of Wayne and State of West Virginia, have invented a new, original, and ornamental Design for a Combined Paper Weight and Photograph Mount, of which the following is a specification, reference being had to the accompanying drawing, forming a part thereof.

Fig. 1 is a front elevational view of a combined paper weight and photograph mount, showing my new design;

Fig. 2 is a side elevational view; and Fig. 3 is a top plan view.

The essential features of my design reside in the parts shown in full lines, the broken lines shown in Fig. 3 having been omitted from Figs. 1 and 2 for convenience of illustration.

I claim:

The ornamental design for a combined paper weight and photograph mount, substantially as shown and described.

JAMES A. MOREHEAD.
